ELASTIC COLLAR AND TIE CLASP

Albert C. Patch, Topeka, Kans.

Application June 30, 1939, Serial No. 282,042

1 Claim. (Cl. 24—81)

The present invention relates to collar and tie accessories, for wearing apparel, and aims to provide an improved device for preserving the neat and desirable appearance of the points or meeting ends of the collar with relation to the tie at the front of the collar.

Accordingly, I have devised an improved collar and tie clasp which is adapted to engage the front ends or points of the collar and hold them in the desired position or in smooth and snug relation to the necktie, with a yielding action which will not interfere with the holding efficiency of the device and at the same time not be likely to release its hold on the ends of the collar and thus become disengaged therefrom in the event of extra strain which is compensated for by the yielding action of the device.

To this end I have devised a clasp construction which comprises a pair of clips adapted for efficient holding engagement with the ends of the collar and connected by an elastic or yielding element adapted to underlie the necktie and span the space between the collar ends and to yield sufficiently to allow for the movements of the wearer while the device is attached in wearing position.

The device is of simple and inexpensive construction, comprising merely the necessary clip elements and their elastic or yielding connecting member, which may preferably be provided with a suitable guard or shield, and all adapted to be given a neat and attractive finish as desired for wearing purposes.

With the foregoing general object in view, the invention will now be described by reference to the accompanying drawing, wherein is illustrated a practical and efficient embodiment of the proposed improvements, after which the features thereof deemed to be novel and patentable will be particularly set forth and claimed.

In the drawing—

Figure 1 is a front elevation illustrating the improved device in wearing position with relation to the front end portions of a collar and a necktie;

Figure 2 is a plan view of the device, on a slightly large scale;

Figure 3 is a sectional detail view on a slightly larger scale, showing the elastic element connecting the clip elements; and

Figure 4 is a similar view showing the yielding connecting element in the form of a coil spring and also equipped with the new sleeve or guard feature.

Referring to the drawing now in specific detail, the improved device is illustrated in the relation

in which it is designed to be worn with reference to the front ends or points 5 of a soft collar 6 of a shirt.

Accordingly, the device comprises a pair of forked or gripping elements, such as the clips 8, each of which has a pair of fingers 9, and at least one of said fingers of each clip having sufficient spring or resilient action so that the clip may be slipped over the edge of the collar and be retained securely in gripping engagement therewith.

The clips or gripping elements 8 are connected to the ends of a suitable elastic or yielding member 10, which is illustrated in Figure 3 as a piece of elastic material of appropriate size and strength for connecting the pair of clips and allowing a sufficient yielding action for accommodating any casual strains imposed upon the device while the same is being worn and without danger of pulling the clips from the gripping engagement with the edges of the collar.

For the purpose of connecting the ends of the elastic 10 to the clips or gripping elements 8, the latter may be provided with suitable slots 12 for insertion of the ends of the elastic and then clamped firmly in place to pinch them securely into gripping relation with the elastic connection, as shown in Figures 2 and 3.

Furthermore, it is preferable to provide a guard or shield, such as the sleeve element 14 of any desired material, to be slipped over the elastic element 10 before it is fastened to the clips, in which position it allows free expanding action of the elastic while acting also as a shield or guard therefor. When the elastic is contracted into normal position, the ends of the guard or shield form stops for engagement with the clips 8, thus aiding in centering the device in correct position, as illustrated in Figure 1.

As a modified form of the elastic or yielding connection, a coil spring element 10' may be substituted in place of the piece of elastic material 10, as represented in Figure 4—this being the form of connection shown in my aforesaid co-pending application Serial No. 272,864 filed May 10, 1939. The connection between the clips 8 and the ends of the spring 10 may be effected in the same manner as in the case of the elastic strip 10, and with the sleeve element 14 slipped over the spring 10' for functioning as a guard or shield for the spring, as already explained.

In devices of this general type now in common use, the gripping means which engage the edges of the collar are joined together by a rigid unyielding construction, which does not, therefore, have any provision for compensating for any

pulling strains; and as a result the whole structure is stiff and rigid and the ends of the device are liable to become detached from the collar.

In the use of the improved device, it is applied as illustrated in Figure 1, in gripping relation to the ends of the collar 5 and with the elastic connection extending underneath and behind the upper knotted portion 14 of the necktie, in which wearing position it will of course give, or yield, to accommodate for any of the pulling strains ordinarily incurred in wearing the device—thereby practically insuring against any accidental detachment of either end of the device from the collar, while at the same time drawing the collar back into correct position. Such a construction is also more comfortable to the wearer as well as neater in its general appearance, and more unlikely to slip out of its proper wearing position.

The parts of the device may be constructed of any appropriate material adapted to take a neat and attractive finish, suitable for this type of garment accessory.

While I have illustrated and described what I

now regard as the preferred form of embodiment of my invention, I desire to be understood as reserving the right to make whatever changes or modifications may fairly be deemed to fall within the spirit or scope of the appended claim.

What I claim and desire to secure by Letters Patent, is:

A collar and tie clasp comprising a pair of forked gripping devices each providing a pair of fingers for gripping engagement with one of the front ends of the collar, a strip of elastic material for underlying the knotted portion of the tie and connecting said gripping devices, the inner ends of the gripping devices being provided with slots receiving the ends of said elastic strip and said slotted ends of said devices being pinched into clamped retaining engagement with the ends of said strip, and a guard sleeve surrounding said strip of elastic material, with the ends of said sleeve forming stops for engagement with the slotted ends of said gripping devices.

ALBERT C. PATCH.
